(Cl. D2—3)

To all whom it may concern:

Be it known that we, David A. McCowan, Jr., Barbara A. McCowan and Peter M. McCowan, subjects of the King of Great Britain, residing in Toronto, county of York, Province of Ontario, Canada, have invented a new, original, and ornamental Design for a Beverage Dispensing Apparatus, of which the following is a specification, reference being had to the accompanying drawings, forming part thereof.

In the drawings:

Fig. 1 is a top plan view of the beverage dispensing apparatus, showing our new design.

Fig. 2 a rear view;

Fig. 3 a front view of the apparatus; and

Fig. 4 is a perspective view of the apparatus.

The other side and rear of the apparatus, not shown, are substantially plain except for the continued beading on the top and bottom borders.

We claim:

The ornamental design for a beverage dispensing apparatus, as shown and described.

DAVID A. McCOWAN, JR.
BARBARA A. McCOWAN.
PETER M. McCOWAN.
